(57) **CLAIM**

The ornamental design of the motorcycle headlamp, as shown and described.

DESCRIPTION

FIG. 1 is a top perspective view showing environmental structure of the top, front, and left sides of a motorcycle headlamp;

FIG. 2 is a top perspective view showing the top, front, and left sides of the motorcycle headlamp;

FIG. 3 is top perspective view showing the top, rear, and left sides of the motorcycle headlamp;

FIG. 4 is a front elevation view of the motorcycle headlamp;

FIG. 5 is a rear elevation view of the motorcycle headlamp;

FIG. 6 is a right side elevation view of the motorcycle headlamp;

FIG. 7 is a left side elevation view of the motorcycle headlamp;

FIG. 8 is a top plan view of the motorcycle headlamp; and,

FIG. 9 is a bottom plan view of the motorcycle headlamp.

The portions shown in broken lines show environment and form no part of the claimed design.
